METHOD OF ROLLING METAL BARS

Gustaf L. Fisk, New Fairfield, Conn.

Application August 19, 1943, Serial No. 499,210

1 Claim. (Cl. 80—66)

This invention relates to the rolling of metal bars of various sectional shapes, commonly known as merchant bars and shapes, whereby they may be finished to precise dimensions within close tolerances, and with improved physical properties. Merchant bars are ordinarily required in such sizes, e. g., in the case of rounds, from $\frac{1}{2}$ " up, that they cannot be delivered in coils for processing operations requiring straight stock, without injury to the material.

In my copending Patent No. 2,369,730, for Method of rolling metal bars, I pointed out the difficulties of rolling metal bars to precise dimensions by the methods and apparatus previously utilized. In said patent, furthermore, I disclosed and claimed a method of rolling bars by passing hot-rolled blanks of cooling-bed length, the sections of which have major and minor axes, through a plurality of stands of cold rolls, while applying tension to the bars between stands sufficient to prevent side-spread of the blank. Such method is entirely practical and feasible where sufficient floor space is available in the vicinity of and immediately beyond the hot mill. Under ordinary circumstances, however, sufficient space is not available and the use of the method of my copending application is thus applicable principally to a new hot mill installation.

I have invented an improvement of the method disclosed in my copending application whereby the essentials of the latter may be utilized in connection with existing hot mills without requiring extensive floor space therein or thereabout. The improved method also makes possible the precision rolling and cold working of a limited range of products with only a relatively small investment in equipment.

In a preferred practice of the invention, I take a hot-rolled blank, the section of which has a major axis and a minor axis differing substantially therefrom, and coil the blank while hot as it emerges from the hot mill, with the major axis of its section parallel to the coil axis. When the coiled blank has cooled substantially to atmospheric temperature, I pickle it and then uncoil it while subjecting it to continuous cold-rolling in a plurality of passes between parallel rolls, while maintaining tension on the blank sufficient to cause the product as delivered from the last pass in the cold rolls to be straight within commercial requirements. I then cut the bar into commercial lengths.

For a complete understanding of the invention and the novel features and advantages thereof, reference is made to the following detailed de-

scription and the accompanying drawings illustrating the practice of my invention as applied to rolling of bars of several different shapes, as well as the cold mill and mill layout which I prefer to employ. In the drawings,

- Figure 1 is a transverse section through a blank suited for cold-rolling in accordance with my invention to produce round bars finished precisely to the required finished dimensions;
- 10 Figures 2 through 5 are partial sections through successive roll stands showing the shape of the passes therebetween, whereby the blank of Figure 1 is progressively reduced to final shape and size;
- 15 Figure 6 is a plan view of a cold mill suited for carrying out the method of my invention;
- Figure 7 is a similar view of a modified form of mill;
- 20 Figure 8 is a plan view of a mill layout in which my invention may advantageously be employed;
- 25 Figure 9 is a similar view showing a modified layout;
- Figure 10 is a view similar to Figure 1 showing the sectional shape of a blank adapted for the rolling of a square bar;
- 30 Figures 11 through 14 are similar to Figures 2 through 5 and show the shapes of the passes between the rolls of the several mill stands whereby the blank of Figure 10 is reduced to final shape and size;
- 35 Figure 15 shows the shape of the starting blank, and Figures 16 through 19 the roll passes, adapted for producing bars of rectangular section; and
- 40 Figure 20 shows the sectional shape of the starting blank, and Figures 21 through 24 the shape of the several roll passes, which I employ for rolling angles.
- 45 Referring now in detail to the drawings and for the present to Figures 1 through 5, in carrying out the method of my invention for the production of round bars, I produce a hot-rolled blank 10 by known rolling methods and apparatus. As shown, the blank 10 has a sectional shape characterized by major and minor axes which differ substantially in magnitude. As the blank is delivered from the last pass in the hot mill, I coil it in a close helix by any suitable form of coiling mechanism, so that the successive turns of the coil have the major axis of their section parallel to the axis of the coil. In this way I avoid any pronounced twist in the blank throughout its length during coiling, by permitting it to coil in the manner offering the least resistance to the bending involved in the coiling operation. I thus compensate for the normal tendency of hot-rolled bars and rounds in par-

ticular, to twist about their own axis as they emerge from a rolling mill. In a bar of considerable length, this twist may amount to a half turn or more, that is to say, the trailing end of the bar may be displaced angularly as much as 180° from the leading end. Unless the roller is alert and the rolls and guides properly maintained and adjusted, the twist may, and frequently does, amount to one or more turns in a length of bar. This twist makes very difficult the subsequent rolling of the bar in a cold mill but I avoid this difficulty entirely by giving the hot-rolled blank a sectional shape characterized by major and minor axes which differ substantially in magnitude, thus eliminating any substantial twist in the blank as it is coiled. When the coiled blank has cooled sufficiently, it is subjected to a conventional pickling operation and is then ready for cold-rolling in a continuous mill such as that shown in Figure 6.

In cold rolling a twisted bar to accurate dimensions, it must be allowed to turn according to its twist in passing through the rolls. Since the several sets of rolls are continuous, however, it follows that such a bar held correctly in the first pass is out of its proper position in the succeeding passes by the degree of twist in the distances from the first to the successive stands.

The pickled coil is placed in a coil holder 11 and the outer end thereof is entered between the rolls 12a and 12b of a horizontal roll stand 12. The rolls of stand 12 have a plurality of grooves 13 therein only one of which is shown in each roll. The grooves are shaped so that the blank on passing through the stand 12 has its minor axis slightly reduced, the major axis being affected little or none. The blank as reduced by the stand 12 is designated 10a. By reason of the difference between the major and minor axes of the section of a blank as it passes through the rolls of stand 12, the blank is rigidly held against twisting as it moves forward to enter subsequent roll stands.

For the sake of simplicity, only one pass has been shown in each set of rolls although the rolls have room for several passes and each set is adjustable longitudinally to bring any pass into alignment with the straight and fixed pass line, along which the bars are made to travel through the rolls of the cold mill.

From the rolls of stand 12, the blank enters the pass between vertical rolls 14a and 14b of the second stand 14. The rolls of this stand have grooves therein effective to reduce the major axis of the blank materially, as shown at 10b. The blank next enters the pass between vertical rolls 15a and 15b of a third stand 15 where its major axis is further reduced to such value that it becomes the minor axis, being less than the original minor axis, as shown at 10c. Finally, the blank enters the pass between horizontal rolls 16a and 16b of the fourth stand 16 having grooves therein effective to reduce the vertical height of the blank precisely to the horizontal sectional dimension, thus converting the blank into a round bar 17 of accurate size and shape.

After passing through the rolls of stand 16, the finished bar may be delivered straight to appropriate means for further processing and handling, for example, as shown in Figures 8 and 9. On the other hand, if desired, the finished product may be coiled by means of a coiler 18 as shown in Figure 7. The mill shown in this figure is otherwise similar to that of Figure 6. The coiler is preferably driven by a suitable motor with con-

75 trol devices appropriate to maintain the desired tension on the portion of the bar between the coiler and the stand 16.

During the successive reductions of the blank by the several stands 12, 14, 15 and 16, I maintain the material between stands under tension by suitably controlling the speeds of the rolls of the several stands. Each stand is preferably driven by an individual motor. Apparatus is commercially available for controlling the speeds of mill motors in relation one to another so as to effect the desired tension of the material and it is unnecessary, therefore, to include here any specific disclosure of the means whereby such tensioning is obtained. The tension is preferably maintained sufficiently high to limit side-spread of the blank in the horizontal roll stands and vertical spread in the vertical roll stands, as fully explained in my copending application above referred to, but also to insure delivery of a straight bar.

It will be recognized that once the blank is started through the pass between the rolls of stand 12, it is firmly held against twisting while it progresses through the remaining cold-rolling stands because of the difference between the major and minor axes of the blank 10 and the fact that the blank is rigid since it is rolled at substantially atmospheric temperatures. The spacing between the several stands 12, 14, 15 and 16, furthermore, is preferably kept at a minimum in order to minimize the detrimental effect of any slight twist remaining in the coiled blank, as the blank proceeds through the several stands, but principally to reduce to a minimum the length at the rear end of the bar which is rolled without benefit of tension.

The exact dimensions of the grooves in the rolls of the several stands may be varied slightly 40 in order to produce several sizes of finished bars from one size and shape of starting blank. By virtue of the straight pass line through the several stands and the tension applied to the blank during rolling, it emerges from the last stand 45 perfectly straight, in addition to being reduced accurately to the required final size and shape.

It is well-known practice to straighten merchant bars by stretching them after the rolling operation has been completed. Bars of superior 50 straightness are obtained in this manner, by equalizing the internal strains in the bar, which cause it to be out of line. It is one of the objects of this invention to roll bars of superior straightness by cold-rolling under tension up to the finishing pass.

Figure 8 shows one mill layout for disposing of bars delivered straight from the stand 16 for further handling and processing. Finished lengths of cold-rolled bars are delivered successively by the last stand 16 of the cold mill indicated generally at 19 in Figure 9 onto a run-out table 20. The bars travel along the table until stopped opposite the transfers 21 and 22. Kick-offs or other suitable mechanisms discharge the bars individually in a sidewise direction from the table 20 to one or the other of the transfers. On the latter, a plurality of bars are collected in batches and then transferred by shuffle bars or other suitable mechanism onto shear-approach tables 23. Batches of bars are delivered by the tables 23 to shears 24 which cut the bars into commercial lengths after which these lengths are delivered from run-out tables 25 to cradles 26 from which they may conveniently be lifted in bundles by an overhead crane.

Figure 9 illustrates a modified form of mill layout providing different paths of travel for the finished lengths of bar, depending on the degree of finish and type of cuts required for the ends thereof. For shearing in the manner described in Figure 8 the bars are delivered to a run-out table 27 and kicked off therefrom to a transfer 28 on which a plurality of bars are assembled in batches for delivery to a shear-approach table 29. From the latter, the batch of bars is delivered to a shear 30, run-out table 31 and cradle 32, in the manner described with reference to Figure 8. If it is desired that the commercial lengths of finished bars have their ends sawed, this may readily be accomplished by the arrangement shown in Figure 9 in which the bars are delivered individually from the run-out conveyor 27 to a transfer 33 and thereby placed on a saw-approach table 34. Alternate bars are moved in opposite directions along this table and successively cut into lengths by saws 35, the lengths being then delivered by run-out tables 36 to skid-beds 37 on which the lengths are collected in batches for removal by crane. A further alternative in the disposition and processing of the cold-rolled bars may be afforded by providing a flying shear 38 at the entry end of the run-out table 27 which is effective to shear the bars immediately to commercial lengths after which the latter pass along the table 27 to a run-out table 39 for delivery to a cradle 40.

The principal advantage of the invention as described above is that one or more continuous cold mills such as shown in Figure 6 can be located at any convenient point, regardless of its relation to the hot mill, since the coiled hot-rolled blank may easily be transported, after cooling and pickling, to the location of the cold mill. The hot mill, furthermore, may be employed as desired for rolling straight bars for delivery to a cooling bed and at other times the hot-rolled product may be coiled for final reduction by cold-rolling, as described herein. It will be understood, of course, that the sections of bars delivered to the cooling bed as hot-rolled will differ from those of the blanks to be further reduced by cold-rolling. By virtue of this invention, therefore, it is possible for an existing hot mill to deliver part or all of its capacity to any cold mill which may be located without particular regard for the location of the hot mill.

The invention also permits important economies in the rolling of merchant bars. The cold-rolling of long lengths of bar, corresponding to cooling-bed lengths or greater may be accomplished with a minimum of equipment. The rate of the cold-rolling operation need not equal the productive capacity of the hot mill since the hot and cold mills operate entirely independently of each other. The production of a relatively few blanks, furthermore, instead of a much larger number of small finished sizes, greatly facilitates the operation and increases the output of the hot mill. At the same time, the whole range of products now finished on the hot mill may be produced by cold-rolling, using only a relatively few shapes of starting blanks. While the invention is limited to sections that can be coiled while hot and started when cooled into a cold mill, this includes a substantial portion of ordinary merchant bars.

The invention is of particular value in meeting demands for a great variety of sizes in small lots. Standardized sizes of coiled blanks may be stored in a coil-storage building and drawn upon as and

when required. The amount of cold work imparted to the bar largely determines its physical properties and suitable blanks can thus be selected to fit particular requirements for properties as well as size of product.

In addition to producing round bars as described above, the invention lends itself to the rolling of bars of other shapes such as squares, flats and angles. Figure 10 shows the section of a starting blank 41 which I employ for rolling squares. Figures 11 through 14 show the shapes of the passes of the several stands of a cold mill similar to that shown in Figure 6, for reducing blank 41 progressively to a finished square bar 42 which is accurate in size and shape within small tolerances. Since the several steps involved in producing the bar 42 from the blank 41 are substantially the same as those required for rolling of rounds as above described, the details 20 need not be repeated.

Figure 15 similarly shows a section of a blank 43 which I use for production of a flat bar 44 by cold-rolling according to the invention. Figures 16 through 19 show the shapes of the several passes required for this reduction. It will be noted that the first and last passes (Figures 16 and 19) are defined by plain rolls and the remaining passes by grooved rolls.

Figure 20 shows a blank 45 suited for the cold-rolling of an angle 46. Figures 21 through 24 show the shapes of the several passes necessary for this product. The first pass (Figure 21) is effective to bend the legs of the blank into right-angle relation and reduce their thickness, without affecting the length of the legs. The second pass (Figure 22) effects a reduction in the length of the right-hand leg to its finished value with a slight resulting thickening, without materially altering the length or thickness of the left-hand leg. The third stand (Figure 23) effects the same operations on the left-hand leg as performed on the right-hand leg by the second stand. The fourth pass (Figure 24) effects a slight reduction in the thickness of the angle legs without changing their length, any excess of metal being converted by extrusion into additional length of the bar. It will thus be appreciated that my method of cold-rolling the blank at Figure 20 to produce an angle involves the successive upsetting of the legs of the blank after bending them to the proper angular relation and a final reduction in the thickness of the legs to finished dimensions.

The advantages of the invention previously pointed out in connection with the rolling of rounds are obviously also obtained in the production of other shapes such as squares, flats and angles. In the coiling of the blanks 41 for squares, the hot-rolled blank may twist slightly until one side or the other engages the mandrel of the coiler or previous turns but, in the case of squares, this degree of twist is not detrimental to the subsequent cold-rolling operation. Angles 65 are coiled as ribbons with their apexes on the outside of the coil. The legs of the blank 45 may spread slightly on coiling but this is fully corrected by the first stand of the cold mill and does not materially hamper entry of the blank thereto.

Although I have illustrated and described only a preferred practice and embodiment of the invention with certain modifications, it will be understood that changes in the apparatus and procedure herein disclosed may be made without de-

parting from the spirit of the invention or the scope of the appended claim.

I claim:

In a method of rolling angles, the steps including coiling a hot-rolled blank V-shaped in section while substantially at rolling temperature, and with the blank disposed substantially in the position of minimum resistance to bending, uncoiling the blank after it has cooled sub-

stantially to atmospheric temperature, passing the blank through reducing passes between a plurality of pairs of cold rolls, thereby first positioning the legs of the angle approximately in their final angular relation, then reducing the lengths of the legs one at a time in separate passes and finally reducing the thickness of the legs to its finished value.

GUSTAF L. FISK.
